UNITED STATES PATENT OFFICE.

ANSELM L. BEDEL, OF BELLEVILLE, ILLINOIS, ASSIGNOR TO EDWARD D. TEMPERLI,
GEORGE A. OBER, HARRY TEMPERLI, AND BERTRAM J. FORD, ALL OF ST. LOUIS,
MISSOURI, DOING BUSINESS AS THE ACE COMPANY.

DESIGN FOR A DOUGHNUT MOLD.

Application filed February 25, 1928. Serial No. 25,589. Term of patent 14 years.

To all whom it may concern:

Be it known that I, ANSELM L. BEDEL, a citizen of the United States, residing at Belleville, Illinois, have invented a new, original, and ornamental Design for a Doughnut Mold, of which the following is a specification, reference being had to the accompanying drawing, forming part thereof.

In the drawing, Figure 1 illustrates a top plan view and Figure 2 a side elevational view of the article embodying my new design.

I claim:

The ornamental design for a doughnut mold, as shown.

ANSELM L. BEDEL.
